UNITED STATES PATENT OFFICE.

JAMES H. BOYE, OF CHICAGO, ILLINOIS.

DESIGN FOR A TIE-BACK FOR SIDE DRAPES.

Application filed April 26, 1929. Serial No. 31,019. Term of patent 7 years.

To all whom it may concern:

Be it known that I, JAMES H. BOYE, a citizen of the United States, residing at Chicago, in the county of Cook and State of Illinois, have invented a new, original, and ornamental Design for Tie-Backs for Side Drapes, of which the following is a specification, reference being had to the accompanying drawing forming part thereof.

In the drawings:

Fig. 1 is a front elevation of a tie-back for side drapes, showing my new design;

Fig. 2 is a side elevation of the same.

I claim:

The ornamental design for a tie-back for side drapes, as shown.

JAMES H. BOYE.
